NATHAN KASDAN, OF NEW YORK, N. Y., ASSIGNOR TO MAJESTIC METAL SPECIALTIES, INC., OF NEW YORK, N. Y., A CORPORATION OF NEW YORK

LOOSE POWDER CONTAINER

Application filed June 10, 1929. Serial No. 369,724.

My invention relates to containers and refers particularly to containers adapted for use with powders.

While the advantages of loose face powders over powder compacts are generally recognized, considerable difficulty has been experienced in producing a satisfactory container for the powder in loose condition.

A container for this purpose must be of such construction that the powder will not escape, or sift out, when not in use, that powder in small quantities may be positively expelled for use and that it be readily operated.

15 The device of my invention possesses all of the above, and other, valuable features, as will be evident upon a consideration of my specification and its accompanying drawings.

20 In the accompanying drawings illustrating one form of the device of my invention, similar parts are indicated by similar numerals.

Figure 1 is a top view of one form of my device in closed position.

25 Figure 2 is a front view of the device of Figure 1.

Figure 3 is an enlarged top view of the device of Figure 1 with the lid in open position.

Figure 4 is a top view of the device of Figure 3 with the delivery member and dispenser in open position and partly broken away for clearness of description.

Figure 5 is a section through the line 5—5 of Figure 1.

35 Figure 6 is a section through the line 6—6 of Figure 5.

Figure 7 is a section through the line 7—7 of Figure 5.

40 Figure 8 is a view in the direction of the arrow of Figure 7.

Figure 9 is a top view of the spring operated plate.

The particular form of the device of my invention illustrated in the accompanying drawings comprises an annular body member having the bottom 11 and the flange side 12. Positioned within the body member is a pressure plate 13 having a plurality of downwardly extended flat resilient members 14, 14, 14, 14 formed by cut-outs from plate 13,

which have a normal tendency to move the plate 13 upwardly. A non-foraminous plate 13A is positioned above and attached to plate 13.

Positioned within the bottom member is an annular dispenser holder ring of U-shaped cross section, having the bottom 15 and the two sides 16 and 17.

Within the dispenser holder ring is a foraminous dispenser 18, having two extended lips 19 and 20 which extend through openings in the wall 17 of the ring, allowing a transverse movement of the dispenser. The dispenser 18 is normally retained in its forward position by means of a flat spring 21, a small projection 22 of the dispenser lip passing through an opening in the spring 21, the two ends of the latter being split, 23, 23, 24, 24, one split end 24 of each spring end entering a small depression in the wall 16 of the dispenser ring.

An annular foraminous delivery member, or cover, 25, is hingedly attached at 26 to the side 12 of the body member. A push button, or operating member, 27, is slidable through a bushing carried by the side 28 of the cover 25 and carries an arc-shaped spring 29.

The U-shaped dispenser ring fits within the delivery member 25, the operating member 27 being opposite the dispenser lip 20, the spring 29 abutting upon the side 17 of the dispenser ring and the faces of the foraminous dispenser 18 and of the foraminous delivery member 25 abutting upon each other. The openings in the last two members are so arranged that they are not aligned when the device is in normal, or unused, position, but which are aligned when the member 27 is pushed inwardly.

The dispenser ring and the delivery member thus form a unit movable upon the hinge 26. These two members are retained in removable connection by means of a spring catch 30 having the push member 31 extending through an opening in the delivery member side 28 and an extended hook 32 which is capable of insertion into an opening in the side 16 of the dispenser ring.

A lid, or cover, 33 is carried by the hinge 26 and has a mirror 34 upon its inner face.

The spring 29 also carries the hook catch 38 capable of insertion above the projection 39 of the cover 33 to retain the device in closed position.

5 When it is desired to introduce powder into the device, the dispenser ring and delivery unit is opened from the bottom member, powder is placed within the dispenser ring which is first preferably inverted from the 10 position shown in Fig. 5 of the drawings, the plate 13 is placed thereon and the device closed.

The operation of the device is as follows:—

As the openings 35, 35 of the dispenser 18 15 and the openings 36, 36 of the delivery member 25 are in non-alignment under normal conditions, no powder can escape. When powder is desired the operating member 27 is pushed inwardly and as the powder is pressed 20 upwardly by the spring operated plate 13, a portion of the powder will be forced through the aligned openings and as the dispenser 18 is moved still further across the device its unperforated portions will cut off this extended powder and make it available for use 25 with the powder puff 37. Upon the release of the operating member 27, the spring 21 will return the dispenser to its original position.

From the drawings it will be seen that the 30 walls of the perforations 36 in the cover 25 are bevelled in a manner to assist in scooping up powder forced through the openings in the dispenser plate 18 and onto the cover 25. These openings have their opposite sides bevelled so as to scoop up powder with movement 35 of the dispenser plate in either direction. Another important advantage of these bevelled edges is to allow the powder puff to take up powder from this bevelled portion of the 40 cover as well as from the flat top of the cover 25. In this way practically all loose powder fed through the dispenser plate is taken up so that substantially none is left on either the dispenser or cover.

45 It will thus be seen that my invention presents a powder container in which the powder is completely retained when the device is not in use and in which during use a small amount of powder is forced outwardly and cutoff from the main powder mass and thus presented for application.

It will be further noted that the amount of powder expelled through each opening of the delivery member is small, being practically 55 that which is massed between the openings of the dispenser and the under face of the delivery plate, these masses being moved by the action of the dispenser into alignment with the openings of the delivery plate and forced 60 therethrough by the pressure of the plate 13 upon the main mass of powder.

The powder in my device, therefore, is prevented from escape when it is not in use, and a small amount of it is expelled by each move- 65 ment of the dispensing member.

From Figs. 4 and 5 of the drawings it may be seen that the dispenser plate 18 moves from the position shown in Fig. 5 through a position in which the perforations of both plates 18 and 25 are open, to a position in which the perforations of both plates are closed, on continued movement of the dispenser plate. During its movement the edges of the dispenser plate perforations tend to scrape or shave the compacted powder. The specific motion just described provides a maximum scraping action for each of the opposite transverse edges of the dispenser plate perforations, with minimum tendency to compact or iron down the compressed powder by the imperforate portions of the dispenser plate.

Hence, my device is a median for a positive expulsion of a small amount of powder by 80 mechanical means.

I do not limit myself to the particular size, shape, number or arrangement of parts, as shown and described, as these are given simply as a means for clearly explaining the device of my invention.

What I claim is:—

1. A loose powder dispenser comprising in combination a container for loose powder, a movable perforate dispensing plate across said container adjacent one end thereof, means for pressing the powder in said container toward said movable plate, a stationary perforate cover plate contiguous and outside of the movable plate, means for operating said movable plate, means for limiting the motion of said movable plate in each direction, the perforations in each plate being substantially uniformly spaced apart in the direction of travel of the movable plate, the extent of such travel being substantially greater than the width of a movable plate perforation plus the width of a stationary plate perforation measured in the direction of travel of the movable plate whereby each plate may function as a shutter for opening and closing the other plate perforations, and the edges of the movable plate perforations transverse to the direction of movement may function to scrape adjacent compressed powder, said dispenser plate being movable from each extreme position of its travel with the perforations of both plates closed, through a position in which the perforations of both plates are open, to a position in which the perforations of both plates are closed by continued movement of said dispenser plate in the same direction.

2. A loose powder dispenser comprising in combination a container for loose powder, a movable perforate dispensing plate across said container adjacent one end thereof, means whereby the powder in said container may be pressed toward said movable plate, a stationary perforate cover plate contiguous and outside of the movable plate, means for

- operating said movable plate, means for limiting the motion of said movable plate in each direction, the perforations in each plate being substantially uniformly spaced apart
- 5 in the direction of travel of the movable plate, the extent of such travel being substantially greater than the width of a movable plate perforation, plus the width of a stationary plate perforation measured in
- 10 the direction of travel of the movable plate whereby each plate may function as a shutter for opening and closing the other plate perforations, and the edges of the movable plate perforations transverse to the direction of movement may function to scrape adjacent compressed powder, said dispenser plate being movable from each extreme position of its travel with the perforations of both plates in one condition through a position in which
- 15 the perforations of both plates are in the opposite condition and by continued movement of the dispenser plate in the same direction to an opposite extreme position in which the perforations of both plates are in their
- 20 same condition as they were at the opposite extreme position, and the spacing between centers of perforations of both plates, measured in the direction of travel, being substantially the same.
- 25 3. A loose powder dispensing vanity case comprising in combination a container for loose powder, a movable perforate dispensing plate across said container adjacent one end thereof, means for pressing the powder in said container toward said movable plate, a stationary perforate cover plate contiguous and outside of the movable plate, means, projecting through the container, for operating said movable plate, from outside
- 30 said container, means for limiting the motion of said movable plate in each direction, the perforations in each plate being substantially uniformly spaced apart, and at least the perforations in the movable plate being elongated in a direction normal to the travel of the movable plate, the extent of such travel being substantially greater than the width of a movable plate perforation, plus the width of a stationary plate perforation measured in
- 35 the direction of travel of the movable plate whereby each plate may function as a shutter for opening and closing the other plate perforations, and the edges of the movable plate perforations transverse to the direction of movement may function to scrape adjacent compressed powder, said dispenser plate being movable from each extreme position of its travel, with the perforations of both plates closed, through a position in
- 40 which the perforations of both plates are open, to a position in which the perforations of both plates are closed by continued movement of said dispenser plate in the same direction, the travel of the movable plate over
- 45 what is necessary to close the perforations

in both plates, providing increased scraping action upon the adjacent powder surface for supplying powder to the perforations of the movable plate in readiness for the next opening of the perforations of both plates and without any substantial travel of said movable plate over the travel necessary to close the perforations of both plates on movement away from the open position.

4. In a loose powder container, in combination; a body member; an upwardly pressed spring operated plate within said body member; a transversely movable foraminous dispenser positioned above said plate; a foraminous delivery member positioned above, and abutting upon said dispenser, the openings in said delivery member being of downwardly extended conical shape, the openings in said dispenser and said delivery member being in non-alignment when the device is in normal position and capable of being positioned in alignment when the dispenser is moved longitudinally and external means for moving said dispenser longitudinally.

5. In a loose powder container, in combination; a body member; an upwardly pressed spring operated plate within said body member; a transversely movable foraminous dispenser positioned above said plate; a foraminous delivery member positioned above, and abutting upon, said dispenser, the openings in said delivery member being of downwardly extended conical shape, the openings in said dispenser and said delivery member being in non-alignment when the device is in normal position and capable of being positioned in alignment when the dispenser is moved longitudinally, external means for moving said dispenser longitudinally, and causing the openings in the dispenser to move across and beyond the openings in the delivery plate.

6. In a loose powder container, in combination; a body member; an upwardly pressed spring operated plate within said body member; a U-shaped dispenser holder ring positioned above said plate; a transversely movable foraminous dispenser carried by said ring and forming a compartment with the bottom member; a foraminous delivery member positioned above, and abutting upon, said dispenser, the openings in said delivery member being of downwardly extended conical shape, the openings in said dispenser and said delivery member being in non-alignment when the device is in normal position and capable of being positioned in alignment when the dispenser is moved longitudinally, external means for moving said dispenser longitudinally and causing the openings in the dispenser to move across and beyond the openings in the delivery plate.

7. In a loose powder container, in combination; a body member; an upwardly pressed spring operated plate within said body mem-

ber; a transversely movable foraminous dispenser positioned above said plate; a hinged foraminous delivery member positioned above, carrying, and abutting upon said dispenser, the openings in said delivery member being of downwardly extended conical shape, the openings in said dispenser and said delivery member being in non-alignment when the device is in normal position and capable 10 of being positioned in alignment when the dispenser is moved longitudinally and external means for moving said dispenser longitudinally.

8. In a loose powder container, in combination; a body member; an upwardly pressed spring operated plate within said body member; a transversely movable foraminous dispenser positioned above said plate; a hinged foraminous delivery member positioned 20 above, carrying, and abutting upon, said dispenser, the openings in said delivery member being of downwardly extended conical shape, the openings in said dispenser and said delivery member being in non-alignment when the device is in normal position and capable 25 of being positioned in alignment when the dispenser is moved longitudinally, exterior means for moving said dispenser longitudinally and causing the openings in the dispenser to move across and beyond the openings in the delivery plate.

9. In a loose powder container, in combination; a body member; an upwardly pressed spring operated plate within said body member; a U-shaped dispenser holder ring positioned above said plate; a transversely movable foraminous dispenser carried by said ring and forming a compartment with the bottom member; a foraminous delivery member positioned above, and abutting upon, said dispenser, the openings in said delivery member being of downwardly extended conical shape, the openings in said dispenser and said delivery member being in non-alignment 40 when the device is in normal position and capable of being positioned in alignment when the dispenser is moved longitudinally, spring means for returning the dispenser to closed position, external means for moving said dispenser longitudinally and causing the openings in the dispenser to move across and beyond the openings in the delivery plate.

10. In a loose powder container, in combination; a body member; an upwardly pressed spring operated plate within said body member; a transversely movable foraminous dispenser positioned above said plate; a hinged foraminous delivery member positioned 55 above, carrying and abutting upon, said dispenser, the openings in said member being of downwardly extended conical shape, the openings in said dispenser and said delivery member being in non-alignment when the device is in normal position and capable of being positioned in alignment when the 60 dispenser is moved longitudinally, causing the openings in the dispenser to move across and beyond the openings in the delivery plate.

11. In a loose powder container, in combination; a body member; an upwardly pressed spring operated plate within said body member; a transversely movable foraminous dispenser positioned above said plate; a foraminous delivery member positioned above, and abutting upon, said dispenser, at least one set of openings being of conical shape, the narrow portion of said openings being directed toward the other foraminous member, the openings in said dispenser and said delivery member being in non-alignment when the device is in normal position and capable of being positioned in alignment when the dispenser is moved longitudinally and external means for moving said dispenser longitudinally. 70

12. In a loose powder container, in combination; a body member; an upwardly pressed spring operated plate within said body member; a U-shaped dispenser holder ring positioned above said plate; a transversely movable foraminous dispenser carried by said ring and forming a compartment with the bottom member; a foraminous delivery member positioned above, and abutting upon, said dispenser, at least one set of openings being 80 of conical shape, the narrow portion of said openings being directed toward the other foraminous member, the openings in said dispenser and said delivery member being in non-alignment when the device is in normal position and capable of being positioned in alignment when the dispenser is moved longitudinally and external means for moving said dispenser longitudinally. 85

13. In a loose powder container, in combination; a body member; an upwardly pressed spring operated plate within said body member; a transversely movable foraminous dispenser positioned above said plate; a hinged foraminous delivery member positioned above, carrying and abutting upon, said dispenser, at least one set of openings being of conical shape, the narrow portion of said openings being directed toward the other foraminous member, the openings in said dispenser and said delivery member being in non-alignment when the device is in normal position and capable of being positioned in alignment when the dispenser is moved longitudinally, spring means for returning the dispenser to closed position and external means for moving said dispenser longitudinally. 90

14. In a loose powder container, in combination; a body member; an upwardly pressed spring operated plate within said body member; a transversely movable foraminous dispenser positioned above said plate; a hinged foraminous delivery member positioned above, carrying and abutting upon, said dispenser, at least one set of openings being of conical shape, the narrow portion of said openings being directed toward the other foraminous member, the openings in said dispenser and said delivery member being in non-alignment when the device is in normal position and capable of being positioned in alignment when the dispenser is moved longitudinally, spring means for returning the dispenser to closed position, external means for moving said dispenser longitudinally, causing the openings in the dispenser to move across and beyond the openings in the delivery plate. 105

beyond the openings in the delivery plate and a lid for said device.

14. A powder container comprising a perforate dispenser plate, means for moving said plate, means whereby powder may be pressed against said plate and through its perforations on movement thereof over the powder surface, a perforate cover above and substantially contiguous said plate for opening or closing the perforations in said plate, portions of said cover being bevelled to scoop up powder passing through the plate perforations.

15. A powder container comprising a perforate dispenser plate, means for moving said plate in two directions, means for pressing powder against said plate and through its perforations on movement thereof over the powder surface, a perforate cover above and substantially contiguous said plate for opening or closing the perforations in said plate, portions of said cover being oppositely bevelled to scoop up powder passing through the plate perforations on movement of said plate in either direction.

16. A powder container comprising a perforate dispenser plate, means for moving said plate, means whereby powder may be pressed against said plate and through its perforations on movement thereof over the powder surface, a perforate cover above and substantially contiguous said plate for opening or closing the perforations in said plate, the walls of the cover perforations being shaped to enable a powder puff to wipe up powder from the walls of said perforations.

17. A powder container comprising a perforate dispenser plate, means for moving said plate, means for limiting the extent of movement of said plate, means for pressing powder against said plate and through its perforations on movement thereof over the powder surface, a perforate cover above and substantially contiguous said plate for opening and closing the perforations in said plate, portions of said cover being bevelled to scoop up powder passing through the plate perforations and to allow a powder puff to wipe up powder from said bevelled portions.

18. A vanity case adapted to dispense loose powder as needed without the danger of powder leaking, which comprises a loose powder container having one side thereof adapted for the discharge of powder and the opposite side provided with an opening for filling the container with powder, a movable cover for closing the said filling opening, a plate on the discharge side of said container, said plate being provided with a shallow recess into which powder is discharged and said recess having at least some of its walls bevelled to facilitate wiping up the powder therein with a puff, and means for guiding at least a portion of the powder across and relative to said plate for cooperation with said

recess for filling said recess with powder whereby said plate may close the container against accidental discharge of powder when said recess is not in communication with said container for reception of powder.

Signed at New York city, in the county of New York and State of New York, this 7th day of June, 1929.
